BIT BRACE

Theodore Hallikas, Marley Neck Road, Md.

Application March 31, 1937, Serial No. 134,147

2 Claims. (Cl. 145—66)

The invention relates to a bit and more especially carpenters' wood boring braces.

The primary object of the invention is the provision of a brace of this character, wherein the same by its construction is susceptible of operation in close quarters or places in that the brace can be readily and quickly converted from a large to a small one or vice versa and is of the ratchet acting type.

Another object of the invention is the provision of a brace of this character, wherein the leverage for the same can be changed at the election of the user of such brace and the scope of utility of the latter is materially enhanced in that the brace can be lengthened or shortened according to the nature of the work operated upon, thus the said brace being of a convertible type.

A further object of the invention is the provision of a brace of this character, which is extremely simple in construction, thoroughly reliable and effective in operation, readily and easily adjusted, strong, durable, and inexpensive to manufacture.

With these and other objects in view, the invention consists in the features of construction, combination and arrangement of parts as will be hereinafter more fully described, illustrated in the accompanying drawing, which discloses the preferred embodiment of the invention and pointed out in the claims hereunto appended.

In the accompanying drawing:

Figure 1 is an elevation of the brace, partly in section, constructed in accordance with the invention, being shown by full lines adjusted to maximum extent, while as shown by dotted lines the brace is converted for congested or close work.

Figure 2 is a top plan view of the hand grip of the brace showing by full lines one adjustment and by dotted lines another adjustment of the same.

Figure 3 is a perspective view of the leverage arm for said grip.

Figure 4 is a perspective view of the stud or journal mount for the said grip.

Figure 5 is a fragmentary elevation partly in section of a leverage arm in substitute for the crank arm of the brace.

Figure 6 is a perspective view of a locking screw employed with the brace.

Similar reference characters indicate corresponding parts throughout the several views in the drawing.

Referring to the drawing in detail, A designates generally the brace constructed in accordance with the invention and comprising a chuck 10 for

accommodating bits, either boring or screw driver types. The chuck 10 has ratchet acting connections 11 with a coupling lever 12 set at right angles to the longitudinal axis of the chuck 10 and such connections 11 are of standard construction or make-up. The outer end of the lever 12 has formed therein a socket 13 intersected by a locking pin hole 14 and into which is removably fitted the latching end 15 of a cranking frame 16, the end 15 being also provided with a pin hole 17 for alignment with the hole 14 for the releasable reception of a locking pin 18 in these holes. The locking pin 18 is formed with an externally threaded shoulder 19 for the threaded engagement in the locking pin hole 14 and also has a freely rotatable grip knob 20 journaled thereon.

The cranking frame 16 at the straight intermediate portion 21 of the same has journaled thereon a roller grip 22 held against displacement longitudinally of the straight portion 11 between shoulders 23 provided on said frame 16.

The frame 16 has at its other end an enlarged socketed terminal 24, its socket 25 being threaded for the separable engagement therein of an externally threaded attaching lug 26 of a journal 27 rotatably supporting a hub 28 for a grip knob or head 29, the hub being formed with a base 30 for the knob or head 29 which is made secure thereto in any desirable manner. The journal 27 is formed with a flat faced wrench engaging shoulder 32 next to the lug 26 and this shoulder accommodates a removable locking screw 33 engageable with the terminal 24 for the fastening of the journal separably connected with said frame 16. It is preferable to have interposed between the journal and the hub suitable antifriction bearings 34.

The hub 28 is detachably fitted rotatably on the journal 27 by a lock washer 35 engaged upon the head end 36 of said journal 27. The knob or head 29 in its bottom portion next to the base 30 has formed therein a guide way 31 for slidable fitting therewith of an extension handle 37 having a key hole shaped slot 38 therein for separable slidable fitting with opposed notches 39 in the journal 27 and further the said handle 37 carries a knob 40 for accommodation within a seat 41 provided in the knob or head 29 when the handle 37 is shifted inwardly with respect to said knob or head 29 and not in use. This handle 37 when 50 inwardly of the knob or head 29 allows free rotation of the said knob or head 29 on the journal 27 and when such handle is pulled outwardly with respect to the latter the same will be locked against rotation on the journal 27. The knob or 55

head 29 has fitted therein a friction leaf spring 42 which plays against the handle 37 to frictionally hold the same in a shifted position. Normally the handle 37 is pushed inwardly of the knob or 5 head 29 so that such knob or head is susceptible of free rotation on the journal 27.

When the frame 16 is separated from the lever 12 by removal of the end 15 of said frame from the socket 13 a short handle 43 can be substituted 10 for this frame 16 and this handle is adapted at the end 44 to fit the socket 13, being provided with a hole 45 for the locking pin 18 while at the other outer end 46 of said handle 43 are carried freely rotatable knobs 47, these being disposed at opposite 15 sides of the end 46 so that both knobs 47 afford a cross grip to the said handle 43. In the use of the handle 43 with the lever 12 increased leverage is obtainable in the use of the brace. The turning spindle 48 for the chuck 10 is formed 20 with an internally threaded socket 49 accommodating the lug 26 of the journal 27 carrying the knob or head 29 so that when this knob or head 29 with its journal 27 is separated from the cranking frame 16, the same may be connected through the 25 lug 26 in the socket 49 in the spindle 48 and in this fashion the brace will be converted to a materially reduced size for the operation thereof in close places or localities with respect to work operated upon.

It is, of course, understood that the chuck 10 of the brace is susceptible of the fitting of wood boring drills or screw driver bits or other work engaging elements therein.

The brace is susceptible for conversion and has 5 a wide scope of utility.

What is claimed is:

1. A brace of the kind described comprising a chuck, ratchet acting means operatively connected with said chuck, a leverage element separably joined with said means, a normally swiveling grip separably journaled on said element, and an arm extensible from and slidably fitted in said grip and latching the latter on the element when in one position for holding said grip against rotation. 15

2. A brace of the kind described comprising a chuck, ratchet acting means operatively connected with said chuck, a leverage element separably joined with said means, a normally swiveling grip 20 separably journaled on said element, an arm extensible from and slidably fitted in said grip and latching the latter on the element when in one position for holding said grip against rotation, and a knob on said arm and inset within the grip 25 when the arm is moved to another position for free swiveling of said grip.

THEODORE HALLIKAS.
